UNITED STATES PATENT OFFICE.

FRANK R. McBERTY, OF EVANSTON, ILLINOIS, ASSIGNOR TO WESTERN ELECTRIC COMPANY, OF CHICAGO, ILLINOIS, A CORPORATION OF ILLINOIS.

PROTECTIVE APPARATUS FOR ELECTRICAL INSTRUMENTS.

No. 800,756.

Specification of Letters Patent.

Patented Oct. 3, 1905.

Application filed December 7, 1904. Serial No. 235,856.

To all whom it may concern:

Be it known that I, FRANK R. McBERTY, a citizen of the United States, residing at Evanston, in the county of Cook and State of Illinois, 5 have invented a certain new and useful Improvement in Protective Apparatus for Electrical Instruments, of which the following is a full, clear, concise, and exact description.

My invention relates to protective apparatus for electrical instruments, such as telephone sets, and has for its object to provide reliable and certain means for protecting the user of such an instrument from injury from abnormal currents with which the circuit-conductors may be accidentally charged.

It is a common practice at the present time to provide telephone-lines in association with electric railways, and portable telephone instruments are furnished to be carried on the 10 cars, these instruments being provided with flexible cords and switch-conductors by which they may be connected with the telephone-line at certain points along the route where connection switch-terminals are located. It 15 has been found that the users of such portable telephone instruments have been frequently subjected to severe shocks from high-tension circuits with which the telephone-circuits may be accidentally crossed. Such high-tension currents will frequently break down 20 the insulation and pass to earth through the body of the user of the telephone, who may receive the discharge either from the frame of the instrument which he is holding or from 25 the flexible conducting-cord. The ordinary insulation of the cord will not be sufficient to prevent the discharge of high-tension currents, and this discharge may take place either to the other conductors of the cord or across 30 the insulating-covering to the user. The present invention is specially designed to offer protection to the user of such an instrument.

My plan is, briefly, to provide a connection-switch for a portable telephone which will 35 complete a direct ground connection for one of the conductors of the flexible conducting-cord leading to the metallic frame of the instrument, the switch being constructed to complete such ground connection before the other 40 conductors are connected to the line. With this arrangement if the telephone-line should be charged with high-tension current such charge would not be transferred to the con-

necting-conductors of the portable instrument until the frame and one conductor of the cord 55 had already been grounded. Any discharge would therefore take place to said grounded conductor instead of through the body of the user. Preferably the extra conductor, which is thus arranged to be grounded to provide a 60 direct path to earth, is wrapped around the other conductors, so that this grounded conductor is interposed between the user and the main circuit-conductors, which are liable to become charged to a dangerous potential. 65

I will describe my invention particularly by reference to the accompanying drawings, and the features or combinations which I regard as novel will be pointed out in the concluding claims.

Figure 1 is a diagram illustrating a portable telephone set and the circuits and apparatus for connecting the same with a telephone-line, the system being equipped with the improved means of my invention for protecting the user of the instrument. Fig. 2 is a detail view of a telephone instrument such as is often used in such portable sets, and Fig. 3 is a view illustrating the manner in which I prefer to assemble the conductors of 80 the instrument in a flexible cord.

The same characters of reference are used to designate the same parts wherever they are shown.

Referring first to Fig. 1, a telephone set is 85 shown provided with circuits and apparatus for connecting the same with a telephone-line running parallel with a trolley-line or other line carrying heavy currents, the system being equipped in accordance with my invention 90 with means for protecting the user of the instrument from heavy currents due to crosses of the telephone-line with the trolley-line. The telephone instrument may comprise a metallic frame *a*, carrying a receiver *a'* at one 95 end thereof and a transmitter *a''* at the other end, the frame thus serving as a handle for the device. Circuit-conductors 1 2 lead from the receiver *a'* of the instrument to the tip and contact pieces *b' b''*, respectively, of a 100 movable connector or plug *b*, a repeating-coil *c* being preferably interposed in said conductors to interrupt the continuity thereof as to direct current while maintaining the circuit of said conductors complete as to telephonic 105 currents.

The transmitter a^2 may be included in a normally open branch or shunt 3 of a portion of conductor 1 between the repeating-coil c and the telephone instrument controlled by 5 a suitable switch d . This branch also includes a local battery e and the primary winding f' of an induction-coil f , the secondary winding f^2 whereof is included in the main circuit-conductor 2. Thus upon the closure 10 of the switch d a local circuit for the battery e is completed, extending from one pole thereof over a portion of conductor 1, through the transmitter a^2 , branch 3, winding f' of induction-coil f , contacts of switch d to the 15 other pole of the battery.

An extra conductor 4 is associated with the circuit-conductors 1 2 and may extend from the frame of the instrument to an extra or sleeve contact b^3 of the said movable connector 20 or plug b , preferably being wound spirally about the circuit-conductors 1 2 of the instrument, as shown. A lightning-arrester g may also be associated with the circuit-conductors 1 2 between the repeating-coil and 25 the movable connector, the plates $g' g^2$ of said arrester being connected with the conductors 1 2, respectively, while the third plate g^3 is electrically connected with the extra conductor 4. 30 The movable connector or plug b is adapted to register with the stationary connection-switch member or spring-jack h , connected with the telephone-line A. The spring-jack is provided with line-springs $h' h^2$, connected 35 with the two limbs of the telephone-line, and an extra contact or thimble h^3 , connected directly to earth. The telephone-line is shown in proximity to a high-tension line, such as a trolley-line B. The two switch members $b h$ 40 are adapted in closing to unite the extra contacts $b^3 h^3$ first, thereby grounding the frame a of the telephone instrument before the circuit-contacts $b' b^2$ of the connector b register with the corresponding line-contacts $h' h^2$ of 45 the stationary switch member. Thus if the telephone-line A should be accidentally crossed with the trolley-line B, as indicated at X, the closure of the extra contacts $b^3 h^3$ of the switch members $b h$ will ground the extra conductor 50 4, leading from the frame a of the instrument and surrounding the main circuit-conductors 1 2 of the cord, before uniting the said main conductors with the charged limbs of the telephone-line. The charge upon the line if strong 55 enough to break through the insulation of the conductors 1 2 of the instrument will take the direct path to earth by way of the extra conductor 4 without shocking or injuring the user of the telephone instrument. The lightning-arrester g also affords a means for diverting such dangerous current from the circuit-conductors 1 2 to the grounded conductor 4.

I prefer to employ a flexible cord for the 65 telephone set, such as illustrated in Fig. 3,

having the several conductors of the instrument formed of flat steel wire compactly arranged and assembled in the manner therein illustrated, the extra or grounding conductor being on the outside to constitute a "grounded shield," so to speak, between the inner main conductors and the user of the instrument.

I claim—

1. The combination with a telephone instrument, of circuit-conductors therefor, a telephone-line subject to crosses with high-tension circuits, a connecting-switch adapted to unite said conductors with said telephone-line, an extra conductor associated with said circuit-conductors and connected with the frame of said instrument, and a direct ground connection for said extra conductor completed in the closure of said connection-switch. 75

2. The combination with an electrical instrument having a metallic frame, of connecting circuit-conductors for said instrument, line-circuit conductors, a connection-switch adapted to unite said connecting-conductors to the line-circuit, a protecting-conductor connected with said metallic frame and wrapped about the circuit-conductors of said instrument, and means for establishing a ground connection for said protecting-conductor in the closure of said connection-switch, 85 before said circuit-conductors are actually united thereby.

3. The combination with an electrical instrument, of a flexible connecting-cord therefor having circuit-conductors and a protecting-conductor wrapped around said circuit-conductors, a movable switch-connector at the end of said cord, having contact-pieces connected with said circuit-conductors and an extra contact connected with said protecting-conductor, and a stationary switch member 100 with which said connector is adapted to engage, said switch member having corresponding circuit-terminal contacts and an extra contact connected to earth, said switch members 105 being adapted in closing to unite the extra contacts first; whereby the user of the instrument is protected from strong currents with which the circuit-conductors may be accidentally charged. 110

4. The combination with an electrical instrument having a metallic frame, of a flexible connecting-cord therefor having metallic circuit-conductors leading from said instrument and a spiral conductor connected with 120 the frame of said instrument and surrounding said circuit-conductors, a plug having contacts connected with said circuit-conductors and having an extra contact connected with said spiral conductor, a spring-jack with 125 which said plug is adapted to register having circuit-terminal contacts and an extra contact connected with earth, said last-mentioned contact being arranged to register with the corresponding extra contact of said plug before 130

the circuit-terminal contacts of said plug and spring-jack are united, substantially as described.

5. The combination with a telephone instrument, of a flexible cord for said instrument having circuit-conductors connected with said instrument, and a spiral conductor connected with the frame of said instrument and surrounding said circuit-conductors, a movable connector having contacts connected with said circuit-conductors and having an extra contact connected with said spiral conductor, a stationary switch member having circuit-terminal contacts and an extra contact connected 15 to earth, a telephone-line subject to crosses with high-tension lines connected with said circuit-terminal contacts of said switch member, the said switch members in closing being arranged to unite the said extra contacts first, 20 whereby the user of the instrument is protected from strong currents with which the line may be accidentally charged.

6. The combination with a telephone instrument comprising a metallic frame having a receiver and transmitter mounted at opposite ends thereof, of a flexible connecting-cord for said instrument having metallic circuit-conductors connected with said receiver and transmitter and a spiral conductor connected 25 with the frame of said instrument and surrounding said circuit-conductors, a plug having tip and ring contacts connected with said circuit-conductors and a sleeve-contact connected with said spiral conductor, a spring-jack 30 with which said plug is adapted to register, comprising line-springs adapted to

register with the tip and ring contacts of said plug and a thimble connected to earth, said thimble being adapted to register with the sleeve of said plug before the line-contacts 40 of said plug and spring-jack are united; whereby the user of the telephone instrument is protected from strong currents with which the line conductors may be accidentally charged. 45

7. The combination with a telephone instrument having a metallic frame, of a movable terminal connector, a pair of main conductors connected with the instrument, a protecting-conductor connected with the frame of the 50 instrument, said movable terminal connector having contacts connected with said main conductors and an extra contact connected with said protecting-conductor, a stationary switch member with which said connector is adapted 55 to engage, said switch having line-contacts and an extra contact connected to earth, said switch members being adapted in closing to join said extra contacts before uniting said line-contacts, and a lightning-arrester having 60 a plate connected with each line conductor of said instrument and a third plate connected with said protecting-conductor; whereby the user of the instrument is protected from strong currents with which the line conductors 65 may be accidentally charged.

In witness whereof I hereunto subscribe my name this 23d day of September, A. D. 1904.

FRANK R. McBERTY.
